UNITED STATES PATENT OFFICE.

VIRGINIA B. PUTNAM, OF MOUNT MORRIS, NEW YORK.

STAMP-HOLDER.

SPECIFICATION forming part of Letters Patent No. 585,700, dated July 6, 1897.

Application filed September 30, 1896. Serial No. 607,430. (No model.)

To all whom it may concern:

Be it known that I, VIRGINIA B. PUTNAM, a citizen of the United States, residing at Mount Morris, in the county of Livingston and State of New York, have invented certain new and useful Improvements in Stamp-Holders; and I do hereby declare the following to be a full, clear, and exact description of the invention, such as will enable others skilled in the art to which it appertains to make and use the same.

This invention relates to a novel construction in a stamp holder and moistener; and it consists in the features of construction and combination of parts hereinafter fully described and claimed.

In the accompanying drawings, Figure 1 is a central vertical section of the stamp holder and moistener constructed in accordance with this invention. Fig. 2 is a side elevation.

Referring now to said drawings, 1 indicates a bottle or receptacle provided with the tube 3, extending inwardly into the same from the upper end thereof in the manner shown. A cap 2 is screw-threaded onto the upper end of the bottle and also a flange 4, rising upwardly therefrom and concentric therewith. This flange 4 is externally screw-threaded to receive the internally - screw-threaded cover 5, as shown.

In the upper end of the tube 3 is a brush

6, whose rear end is made in such a manner that it can receive its moisture from the tube. It will be seen that should an excess of water enter the brush 6 and be squeezed out of the same it will be collected by the receiving rim 4, so that it cannot be absorbed by the brush. The lower portion of the bottle 1 is exteriorly screw-threaded to enter the screw-threaded box 7, in which stamps can be placed, as shown.

Having thus described my invention, what I claim as new, and desire to secure by Letters Patent, is—

In a device of the kind specified, a bottle having a screw-threaded lower and upper end portion, a central tube 3 extending into the bottle from the upper end thereof, a screw-threaded cap secured to the upper end 45 of the bottle and provided with an uprising externally - screw-threaded flange, a screw-threaded cover fitting upon said screw-threaded flange, a brush secured in the outer end portion of said tube, and a box 7 having a 50 screw - threaded receptacle to receive the lower end portion of said bottle.

In testimony whereof I have signed this specification in the presence of two subscribing witnesses.

VIRGINIA B. PUTNAM.
